ORE CONCENTRATOR

Wayne I. Noble, Denver, Colo.

Application May 19, 1951, Serial No. 227,145

2 Claims. (Cl. 209—465)

1

This invention relates to mechanisms for concentration or dressing of ores of the type in which crushed rock or earthy materials are agitated so as to concentrate the metallic ingredients and rich mixtures of metal and other ingredients in a portion of the container where they are readily separable from waste materials.

The main objects of this invention are to provide an improved valve structure for holding back the undesirable materials while dumping the concentrated metal containing mass; to provide improved means for adjusting the position of such valve structure so as to adapt the container readily to efficient use in connection with various particular compositions of the crude mass of material to be handled; and to provide improved means for dumping the materials from the two compartments of the container in separate places.

A specific embodiment of this invention is illustrated in the accompanying drawings, in which:

Figure 1 is a side view, partly in section and partly schematic, of a mineral concentrator constructed according to this invention.

Fig. 2 is a fragmentary detail of the same showing the manner in which the plates that constitute the bottom closure of the container are swung down for dumping the contents of the lower compartment.

Fig. 3 is a similar fragmentary section of the parts shown in Fig. 2, as viewed from the line 3—3 of Fig. 1.

Fig. 4 is a section taken on the line 4—4 of Fig. 1 showing the valve parts in their open position.

Fig. 5 is a similar view showing the valve parts in their closed position.

Fig. 6 is a developed section taken on the curved line 6—6 of Fig. 4 showing the relation of the valve plates to each other in their open positions.

Fig. 7 is a similar section taken on the line 7—7 of Fig. 5 showing the closed positions of the parts.

In the form shown in the drawings, the mineral concentrator comprises an upright cylindrical container 10 open at both ends and subdivided into a large upper chamber 11 and a relatively small lower chamber 12 by means of a valve structure 13 that extends horizontally across the interior of the container 10 and is adjustable vertically to vary the relative proportions of the chambers 11 and 12. The bottom closure is preferably of downwardly convex, dished formation and comprises a pair of plates 14 of semi-circular contour, abutting each other along the diameter represented by the line 3—3 of Fig. 1 and con-

2

tacting marginally with the bottom rim of the container 10.

These plates 14 are separately hinged on a pair of parallel shafts 15 journaled in bearings 16 mounted on the bottom rim 17 of the container 10. Each of the plates 14 has a pair of hinge arms 18 that are fast on the respective shafts 15 and have intermeshing gear teeth that cause the plates 14 to swing in unison in opposite directions between open and closed positions through the turning of one of the shafts 15, which latter shaft has a lever arm 19 at one end positioned so as to engage a stationary abutment 20 when the receptacle 1 has been shifted sidewise to a position where the contents of its compartment 12 are to be dumped. This abutment 20 is indicated in Fig. 2 in its relation to the lever 19 during the dumping operation.

As is usual in devices of this kind, means such as the paddles 21 and 22 are provided for stirring and agitating the mass of the contents of the receptacle 10 in a systematic manner so as to cause the metallic and metal containing parts of the ingredients to settle toward the bottom of the receptacle while the lighter particles are lifted, by action of the paddles and floatation, to the upper compartment of the receptacle 10.

The valve structure 13 comprises a main non-rotatable plate 23 having a circular rim portion 24 that has loose sliding contact with the walls of the container 10 and is rigidly affixed to an annular series of vertical posts 25 which are shiftable vertically so as to raise and lower the structure 13 to increase or decrease the relative capacity of the compartment 12 with respect to the compartment 11.

The valve plate 23 comprises a plurality of sector-shaped radial vanes 26 separated by wider spaces 27 through which spaces the ore may pass from compartment 11 to compartment 12 when the valve is open. Cooperating with the plate 23 is an upper valve plate 28 and a lower valve plate 29 comprising vanes and spaces corresponding in angular width to those of the fixed plate 23.

The plates 28 and 29 are shiftable in opposite directions so as to cooperate in fan fashion with the plate 23 for opening and closing the spaces 27, as will be understood from Figs. 4, 5, 6 and 7. With these plates, as shown, the vanes in their open position occupy only one-third of the transverse area of the container and two-thirds of this area is open. Due to the opposite motion of the upper and lower valve plates, the opening and closing of the valve are accomplished with a minimum of motion of the crank 51.

In the form shown, the posts 25 are threaded in nuts 30 that are journalled in bearing apertures in the rim 17 and shouldered to secure them against vertical movement with respect to the rim 17. Each nut 30 has fast thereon, below the rim 17, a gear 31 by means of which the nut 30 is rotated. The posts 25 are secured against rotation in the rim 24, so that simultaneous rotation of the nuts 30, as by means of a ring gear 32 meshing with the gears 31, will raise and lower the valve structure as a unit. The lower ends of the posts 25 may have bolt heads 33 to limit the upward movement of the valve structure. As indicated in Fig. 1, the ring gear 32 may be driven by a beveled gear 34 rotated by hand crank 35.

Rotation of the paddles 21 and 22 and that of the movable valve plates is accomplished in the device shown by means of a central shaft 39 and a plurality of concentric quill shafts or sleeves 37, 38 and 39 journalled in bearings 40 and 41 along the vertical axis of the receptacle 10. The shaft 36 and the sleeve 39 that drive the paddles 21 and 22 are power driven, as represented schematically by the motor 62, gears 43 and chain belts 44 and 45.

The upper valve plate 28 is rotated by means of a flanged hub 46 attached to the plate 28 and splined to its respective shaft 38 so as to be rotated by that shaft 38 but vertically slidably along it. Similarly, the lower valve plate 29 is fast on a flanged hub 47 that is splined to the inner quill shaft 37. The quill shafts 37 and 38 are rotated by beveled gears 48 and 49 respectively which in turn are driven by a beveled pinion 50 rotatable by hand by a crank 51. The shaft 35 and the quill shafts 37, 38 and 39 are, of course, appropriately held against relative axial shifting.

The operation of the device shown is as follows:

In general, the concentrator operates according to usual practices in which a mass of finely ground ore, together with water or other suitable liquid, is dumped into the container 10 and stirred and agitated for a period of time found to be necessary to cause the metal ingredients and a minimum of other earthy materials to accumulate in the bottom chamber 12 of the receptacle, while the waste materials, which are lighter than the metal-containing particles, drift upward in the semiliquid mass and occupy the upper chamber 11.

The purpose of the present invention is to provide for separating the metal-bearing contents from the great mass of other material by the use of a valve-like partition that holds back the other material while the metal-containing portion of the mass is withdrawn at the bottom of the container and to have the valve means adjustable vertically within the container so that this separation will conform as closely as possible to the relative proportions of these two masses after the mineral concentration has been effected according to the nature of the materials handled.

The valve plates are in the open position during the operation of concentrating the metal-containing mass into the lower chamber 12. When in the judgment of the operator, the separation of the mineral contents from the main bulk of the mass has been accomplished, he turns the crank 51 causing the valve to close. In this operation, the beveled gear 50 causes the gears 48 and 49 to rotate in opposite directions and through their shafts 37 and 38 respec-

tively cause the plates 29 and 28 to rotate in opposite directions from a position of registration with the fixed plate 23, until the advancing edges of the plates 28 and 29 reach the limit of their closing movements, with all of the valve segments of the plates meeting edge-to-edge in slightly overlapping relation, as indicated in Fig. 7.

The movable valve plates are limited in their opening and closing movements by suitable stops which may take the form of abutments on the fixed plate 23, as represented, for example, by pins 52 and 53, shown in Figs. 4 and 5, which limit the movement of the upper valve plate 28 in its open and closed positions respectively.

So long as the percentage of metallic ingredients in the ore mass remains roughly constant, the vertical adjustment of the valve plates need not be disturbed after the best position thereof has once been determined.

When it is desired to shift the position of the valve plates to change the relative capacity of the chambers 11 and 12 of the container, the operator rotates the crank 35 causing the beveled gear 34 to rotate the ring gear 32 which, in turn, rotates the gears 31 and nuts 30, causing the posts 25 to raise or lower the fixed valve plate 23, carrying with it the rotatable valve plates 28 and 29. This is accomplished without disturbing the axial relation of the shafts 36 to 39 inclusive, due to the splined connection between the hubs of the movable valve plates and their respective shafts.

After the valve has been closed, upon the completion of the separating or dressing operation, the container 10 is shifted sidewise until the lever 19 strikes an abutment 20, causing the bottom closure plates 14 of the compartment 12 to swing to their depending positions through the interaction of the gear teeth on their arm 18, causing the contents thereof to be discharged into an appropriate bin that is not shown. Continued movement of the receptacle 10 may carry it to a suitable dump where, upon opening of the valve by rotation of the crank 51, the contents of the chamber 11 will be discharged.

Although but one specific embodiment of this invention is herein shown and described, it will be understood that numerous details of the structure shown may be altered or omitted without departing from the spirit of the invention as defined by the following claims:

I claim:

1. In a mineral concentrator, comprising a cylindrical ore dressing receptacle having a discharge closure at the bottom end thereof, a valve spaced upward from said closure and extending across the interior of said receptacle to divide the same into upper and lower chambers, said valve comprising a main plate and a pair of relatively rotatable plates slidably mounted one upon another in laminar arrangement, said plates having circular rims and being similarly shaped to provide radiating sector-shaped vanes alternating with sector-shaped openings approximating twice the angular width of the vanes, means operatively connected to said rotatable plates for simultaneously rotating them in opposite directions between positions where their vanes register with the vanes of said main plate and positions where the vanes of one of said rotatable plates coact with those of the other for opening and closing said openings, and means connecting said valve to said receptacle for raising and lowering said valve within said recep-

tacle to change the relative capacities of said chambers.

2. In a mineral concentrator, comprising a cylindrical ore dressing receptacle having stirring devices therein and having a discharge closure at the bottom end thereof, a valve spaced upward from said closure and extending across the interior of said receptacle to divide the same into upper and lower chambers, said valve comprising a main plate and a pair of relatively 10 rotatable plates mounted one upon another, said plates having circular rims and being similarly shaped to provide radiating sector-shaped vanes alternating with sector-shaped openings approximating twice the angular width of the vanes, 15 means for simultaneously rotating said movable plates in opposite directions between positions where their vanes register with the vanes of said main plate and positions where their vanes coact for opening and closing said openings, and 20 means for raising and lowering said valve within said receptacle to change the relative capacities of said chambers, said last-named means comprising a plurality of posts attached to the rim of said main plate and extending below the 25

bottom of said receptacle, and means for simultaneously raising and lowering said posts.

WAYNE I. NOBLE.
